CLAIM

The ornamental design for a boot for use in an architectural-structure covering as shown and described.

DESCRIPTION

FIG. 1 is a perspective view of a boot showing our new design with features illustrated in broken lines for illustrative purposes and thus not constituting a part of the claimed design;

FIG. 2 is a left side elevational view of the boot of FIG. 1; FIG. 3 is a right side elevational view of the boot of FIG. 1; FIG. 4 is a rear elevational view of the boot of FIG. 1; FIG. 5 is a front elevational view of the boot of FIG. 1; FIG. 6 is a top plan view of the boot of FIG. 1; and, FIG. 7 is a bottom plan view of the boot of FIG. 1.

The broken lines in the drawings are environmental and for illustrative purposes only depicting portions of the boot that form no part of the claimed design.

The unshaded surfaces shown between the solid lines and the broken lines form no part of the claimed design.
